UTILITY CONTROL, SUPPLY AND SERVICE UNIT FOR LABORATORY TABLES

Alton F. Sautter, Chicago, Ill., assignor to Water Saver
Faucet Co., Chicago, Ill., a proprietorship

Filed Apr. 3, 1962, Ser. No. 69,561

Term of patent 14 years

(Cl. D16—2)

Fig. 1.

Fig. 2.

Fig. 3.

FIG. 1 is a front elevational view of a utility control supply and service unit for laboratory tables showing my new design;

FIG. 2 is a side elevational view thereof, the opposite side being substantially the same; and

FIG. 3 is a top plan view thereof.

The dominant features of my design reside in those portions shown in full lines.

I claim:

The ornamental design for a utility control, supply and service unit for laboratory tables, substantially as shown and described.
